No. 737,617.

PATENTED SEPT. 1, 1903.

M. T. HARRIGAN.
CHANNEL LAYING MACHINE.
APPLICATION FILED SEPT. 13, 1902.

NO MODEL.

THE NORRIS PETERS CO., PHOTO-LITHO., WASHINGTON, D. C.

UNITED STATES PATENT OFFICE.

MICHAEL T. HARRIGAN, OF WOLLASTON, MASSACHUSETTS, ASSIGNOR TO PEERLESS MACHINERY COMPANY, OF CHARLESTON, WEST VIRGINIA; NEW YORK, N. Y., AND BOSTON, MASSACHUSETTS.

CHANNEL-LAYING MACHINE.

SPECIFICATION forming part of Letters Patent No. 737,617, dated September 1, 1903.

Application filed September 13, 1902. Serial No. 123,281. (No model.)

To all whom it may concern:

Be it known that I, MICHAEL T. HARRIGAN, a citizen of the United States, and a resident of Wollaston, county of Norfolk, State of Massachusetts, have invented an Improvement in Channel-Laying Machines, of which the following description, in connection with the accompanying drawings, is a specification, like numerals on the drawings representing like parts.

This invention has for its object the production of a novel machine for laying or smoothing down the channel-flaps of a sole to cover the stitches or fastenings of what ever character which are used to unite the sole to the upper in the process of making the shoe.

The invention comprises a flexible rotating channel-flap-laying member having right and left spirals thereon and manually-operated means to control the degree of flexure of said member, whereby the active portion of the face of said member may be made to accommodate itself to any contour of the sole.

In the best form of my invention now known to me the channel-flap-laying member is a two-part member, which is carried by a suitable non-rotating supporting member, about which said laying member is capable of being rotated. The two rotative parts of the laying member are flexibly connected together and preferably occupy normally a position substantially in alinement. Each part of the laying member has spiral ribs thereon, the ribs on one member being right-hand and those on the other member left-hand. The supporting member, about which the member rotates, is shown as a cylindrical pivot-rod extending through the axis of the channel-flap-laying member and jointed intermediate its ends and at a point coinciding with the flexible connection between the two parts of said laying member. Suitable manually-operated means are provided for bending the supporting member or pivot-rod at its joint that the laying member may be made to conform to the convexity of the sole. Means are provided for positively rotating about the supporting member the laying member, the flexible connection between the two parts of

the laying member permitting of the rotation thereof at any position of the pivot-rod. This construction permits of giving the portion of the face of the rotary laying member which is contacting with the sole either a straight shape or more or less of a convex shape, according to the contour of the sole being operated upon.

In the drawings, Figure 1 is an elevation of my improved machine in one of the best forms now known to me, the dotted lines showing a part of a shoe in a position to be operated upon. Fig. 2 is a view of a portion of my machine, showing the channel-flap-laying member in a different position; and Fig. 3 is a vertical section through the rotary channel-flap-laying member.

The machine comprises a suitable base or standard 3, on which is mounted a head 4 of a shape to carry the operative parts of the machine, said head in this embodiment of my invention being shown as an overhanging arm.

The channel-flap-laying member or smoothing member is a flexible member and comprises two parts 5 and 5^a, which have on their periphery the spiral smoothing or flap-laying ribs 6, the ribs on the part 5 being right-hand spirals and those on the part 5^a being left-hand spirals. The two parts of the laying member are flexibly connected together in some suitable way, so as to permit the member to rotate even though the two parts have an angular relation to each other, and in Figs. 1 to 3 I have shown the flexible connection in the form of a universal joint. The particular universal joint shown comprises a ring 7, to which the members 5 5^a are pivoted at right angles to each other. The member 5 has ears or lugs 8, carrying pivot-points 9, which engage suitable sockets in the ring 7, and the member 5^a also has oppositely-disposed lugs 8^a, carrying similar pivot-points 9^a, which also have pivotal bearings in the ring, the lugs 8^a being situated at right angles to the lugs 8. The two-part laying member is mounted upon a suitable non-rotatable supporting member, shown as a pivot-rod or shaft, and said laying member is capable of rotating thereabout. The pivot-rod, which is designated by 10, has a joint 11 intermediate its ends and situated

at the center of motion of the universal joint. The said rod 10 is pivoted at one end to the frame, as at 13, while the other end is pivotally connected to the link 14, which in turn 5 is pivoted to the end of the arm 4, as at 15. This construction allows the rod either to assume a straight position or a position in alinement, as illustrated in Figs. 1 and 3, or permits it to be bent upwardly at its joint, as 10 shown in Fig. 2. The rod is herein illustrated as having collars 16 thereon, between which the two parts of the channel-laying member are confined and by which they are prevented from movement longitudinally of the rod. 15 Any suitable means may be employed for rotating the flap-laying member, and, as herein illustrated, a driving-pulley 20 is made fast to one part of said member.

It will now be seen that when the parts are 20 in the position shown in Fig. 1 the surfaces of the two parts of the flap-laying member are in alinement with each other and form, in effect, a straight cylindrical surface having right and left spiral ribs thereon. When 25 the pulley is rotated in the direction of the arrow, Fig. 1, the ribs 6 will act gradually from the central part of the sole to the outer edge thereof and will meet the channel-flap and turn the same over into its original position to cover the channel and conceal the fastenings which unite the sole to the upper. It sometimes happens that the sole is more or less rounding, and by jointing the rod and constructing the rotary laying member in two 30 parts flexibly united said laying member may be made to assume the position shown in Fig. 2 or any other flexed position, according to the contour of the sole.

I have herein provided means for manu- 40 ally controlling the degree to which the rotating member may be flexed, and in one form of my invention the rod or shaft 10 will be projected beyond the pivot 13, as at 23, and said end connected by the link 24 to the 45 treadle 25. A suitable spring 26 serves to normally maintain the rod in a straight-line position, and suitable stops 27 and 28 prevent the rod from being bent except upwardly at the center.

50 In using the device the operator places his foot upon the treadle 25 and by depressing the same more or less controls the degree to which the rod 10 is bent, and thereby adapts the under side of the laying member to the 55 contour of the sole.

In the preferred embodiment of my invention herein represented both parts of the flap-laying member are shown as being driven by a single pulley 20 on one of said parts, and 60 when this construction is employed it is necessary, of course, that the two parts 5 and 5^a should be flexibly connected together in such a way that they are locked together for rotary movement, but can assume any angular position relative to each other. My invention is not limited, however, to the particular means shown for driving the laying

member nor for flexibly connecting the two parts of the laying member. My invention is broad enough to include any means for driving said member positively and for flexibly connecting the parts thereof that they may 70 rotate in unison.

From the above it will be obvious that various changes may be made in the construction of the apparatus shown without departing in any way from my invention, and consequently I reserve to myself the right to make any and all such changes as come within the scope of the appended claims. 75 80

Having described my invention, what I claim, and desire to secure by Letters Patent, is—

1. In a device for laying channel-flaps, a flexible rotary laying member having right 85 and left spirals, a jointed, non-rotatable rod carrying said member, and manually-operated means to flex said rod and laying member and cause the active portion of said laying member to conform to the contour of the 90 sole being operated upon.

2. In a device of the class described, a two-part rotary laying member jointed together at their contiguous ends and provided with right and left spiral ribs, and means to sustain and to rotate said laying members. 95

3. In a device of the class described, a pivot-rod jointed intermediate its ends, a two-part rotary laying member supported by said rod and rotatable thereabout, the two parts of 100 said laying member being flexibly connected together, and means to rotate said laying member.

4. In a device of the class described, a jointed pivot-rod having a pivotal connection at 105 each end with a fixed support, a two-part channel-flap-laying member rotatable about said rod, the parts of said member being flexibly connected together, and means to rotate said member. 110

5. In a device of the class described, a pivot-rod jointed intermediate its ends, a two-part laying member supported by said rod and rotatable thereabout, the two parts of said member being connected together by a universal 115 joint, means to rotate said member, and manually-operated means to flex said rod.

6. In a device of the class described, a jointed pivot-rod having a pivotal connection at each end with a fixed support, a two-part 120 channel-flap-laying member rotatable about said rod, the parts of said member being connected together by a universal joint, means to rotate said member, and manually-operated means to flex said rod. 125

7. In a device of the class described, a two-part jointed non-rotatable supporting member normally in alinement one with the other, a two-part channel-flap-laying member having a central flexible connection to permit said 130 two parts to rotate in unison about said supporting member, and enable one part to assume an angular abnormal position inclined with relation to the other part of said laying

member that the latter may conform to the convexity of the sole, and means to rotate said laying member positively about said supporting member.

5 8. In a device of the class described, a shaft, a two-part channel-flap-laying member having a central flexible connection, one having a right and the other a left spiral projection, a pulley connected with one of said members, 10 and adapted to receive a belt by which to rotate said two-part member about said shaft.

9. In a device of the class described, a two-part channel-flap-laying member, a support on which the said laying member is revolvably 15 mounted, and means to rotate said laying

member positively upon said support, the laying member and support being capable of being flexed or bent out of alinement to enable the laying member to conform to the convexity of the sole and act upon the channel-flaps at 20 each side thereof and lay the same over to close the channels with which they are connected.

In testimony whereof I have signed my name to this specification in the presence of 25 two subscribing witnesses.

MICHAEL T. HARRIGAN.
